UNITED STATES PATENT OFFICE.

SALEM R. HART, OF CLEVELAND, OKLAHOMA, ASSIGNOR OF ONE-HALF TO JOHN L. PRIMM, OF CLEVELAND, OKLAHOMA.

ROD-CO尤LING.

1,157,103.

Specification of Letters Patent.

Patented Oct. 19, 1915.

Application filed November 28, 1914. Serial No. 874,563.

To all whom it may concern:

Be it known that I, SALEM R. HART, a citizen of the United States, residing at Cleveland, in the county of Pawnee and State of Oklahoma, have invented certain new and useful Improvements in Rod-Couplings, of which the following is a specification, reference being had to the accompanying drawings.

10 This invention relates to certain improvements in rod couplings and has relation more particularly to a device of this general character especially designed and adapted for use in connection with suction rods or the like; and the object of the invention is to provide a coupler of this character having novel and improved means whereby the same may be readily connected or disassembled, as the occasion may require, with a minimum of labor and within a minimum of time.

The invention consists in the details of construction and in the combination and arrangement of the several parts of my improved rod coupling whereby certain important advantages are attained and the device is rendered simpler, less expensive and otherwise more convenient and advantageous for use, all as will be hereinafter more fully set forth.

The novel features of the invention will be carefully defined in the appended claim.

In order that my invention may be the better understood, I will now proceed to describe the same with reference to the accompanying drawings, wherein—

Figure 1 is an elevational view illustrating a rod coupling constructed in accordance with my invention; Fig. 2 is a sectional view taken substantially on the line 2—2 of Fig. 1; and Fig. 3 is a fragmentary view, partly in elevation and partly in section, of the female member included in the present embodiment of my invention.

45 As disclosed in the accompanying drawings, 1 denotes coacting sections of a rod, the adjacent extremities whereof being provided, respectively, with the male member 2 and the female member 3.

As herein set forth, the female member 3 is bifurcated with the lower extremity 4 of the kerf 5 being substantially V-shape while the upper extremities of the opposed walls of the kerf 5 are provided with the inwardly disposed shoulders 6, the lower edges 7 whereof being substantially V-shape in elevation and being undercut, as indicated at 9.

The male member 2 is provided with the flattened elongated extension 10 adapted to be accommodated within the kerf 5 and having its free extremity provided with a substantially V-shape head 11, the upper edges 12 whereof being also substantially V-shape in form and undercut, as indicated at 14, and adapted to interlock with the shoulders 6 whereby it will be perceived that an effective connection is created between the members 2 and 3. It is thought that the manner of assembling or disconnecting the members 2 and 3 is clearly apparent to those skilled in the art to which my present invention appertains.

From the foregoing description, it is thought to be obvious that a rod coupling constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

40 A rod coupling consisting of a female member having one extremity bifurcated, the free extremities of the opposed walls of the kerf being provided with inwardly disposed shoulders, the lower edges of which being substantially V-shape and undercut, and a male member provided with an extension adapted to be accommodated within

the kerf of the female member, the free extremity of the extension being provided with a head having its inner faces substantially V-shape in form and undercut to interlock with the shoulders of the female member.

In testimony whereof I hereunto affix my signature in the presence of two witnesses,
SALEM R. HART.

Witnesses:

L. D. BROWER,
CHAS. GILLESPIE.
